UNITED STATES PATENT OFFICE.

WILLIAM SCHEER, OF ARVERNE, NEW YORK.

DESIGN FOR A BROOCH.

SPECIFICATION forming part of Design No. 23,461, dated July 17, 1894.

Application filed May 22, 1894. Serial No. 512,124. Term of patent 7 years.

To all whom it may concern:

Be it known that I, WILLIAM SCHEER, a citizen of the United States, residing at Arverne, in the county of Queens and State of New York, have invented and produced a new and original Design for a Brooch or Pendant, of which the following is a specification, reference being had to the accompanying drawings, in which—

Figure 1 is an elevation, and Fig. 2 a plan view of my design mounted as a brooch.

The leading feature of my design consists in a configuration representing a bird with a series of surface ornaments.

In outline the configuration is in part curved and in part scalloped, and the surface is convex and comprises series of grouped and contrasting small circles and projecting figures representing the lines of prominent feathers.

What I claim is—

The design for a brooch or pendant, substantially as shown and described.

Signed by me this 9th day of May, A. D. 1894.

WILLIAM SCHEER.
